DRIVE CONTROL MECHANISM FOR PRIME MOVER WITH FLUID ACTUATED CLUTCHES

Arthur F. Grant, Cleveland, and Robert R. King, Lakewood, Ohio; said Grant assignor to General Motors Corporation, Detroit, Mich., a corporation of Delaware

Application December 24, 1957, Serial No. 705,006

24 Claims. (Cl. 192—.098)

This invention relates to control apparatus of the fluid pressure type for selectively controlling the speed of a unidirectional prime mover and the selective operation of clutches for controlling the speed and direction of an output member and has particular application to maneuvering control systems for marine propulsion drives.

Where a prime mover on a ship is operative in one direction only, it is customary to employ either a reversible electrical drive or forward and reverse clutches for selectively controlling the rotational direction of the propeller and hence the propulsion of the ship in either the forward or the astern directions. Prior to the instant invention, the operating characteristics of reversible electrical drives have generally been deemed to be much superior to those of reversible clutch drives, providing a responsiveness, a fineness, and an adaptability of control not considered possible with a clutch drive. However, such electrical drives and the controls therefor are relatively complex and expensive. Hence, reversible clutch drives have been utilized quite extensively in those applications where a high degree of fineness and responsiveness of control have not been required. With such clutch drives it is of course necessary to match the starting and running torque characteristics of the individual clutches with the speed and torque characteristics of the prime mover.

To reverse the direction of operation of the propeller with a reversing clutch drive, it is only necessary to disengage the one clutch and to subsequently engage the other. However, to minimize the power dissipation or work imposed on the oncoming clutch and thereby clutch wear and to prevent damage to the clutches on other parts of the power transmitting mechanism upon clutch engagement, it has generally been desirable that the prime mover and the propeller first be brought to and maintained at a low speed such as the idling speed of the prime mover before disengagement of the operating clutch and energization of the other clutch for engagement. To minimize the possibility of stalling the engine during such low engine speed clutch engagement the engine idle fuel setting has necessarily been established at a rate higher than that which would otherwise have been required thus reducing overall operating efficiency of the power plant or provision has been made in the control mechanism for advancing the engine fuel setting slightly above its idle rate during the clutch engaging period.

The invention contemplates the provision of a simple, rugged, foolproof and relatively inexpensive marine drive and control system for a prime mover having speed setting means and ahead and astern driving clutches and including an improved single-lever maneuvering control mechanism interconnecting the speed setting means and clutches and adapted to provide controlled clutch engagement comparable in smoothness and controllability to an electrical drive and further to provide a controlled increase in the speed setting of the prime mover and in the torque transmitting capacity of the engaged clutch after

initial full engagement of either clutch in response to manual movement of the maneuvering control lever between a neutral zone and full speed ahead and astern controlling positions.

5 The combined means by which the foregoing objectives are accomplished, together with other novel features and advantages of the invention, will become more apparent from the following detailed description of several embodiments thereof having reference to the accompanying drawings in which:

Figures 1 and 1a are diagrammatic views, partly in section and partly in outline, of complementary portions of an engine speed and clutch engagement control mechanism embodying the invention;

15 Figure 2 is a graph showing the interrelationship between engine and output shaft speed and clutch inflation pressure for the embodiment of the invention shown in Figures 1 and 1a;

Figure 3 is a graph showing the operating cycle of the 20 form of the invention of Figures 1 and 1a in a full ahead and full astern reversal;

Figure 4 is a graph similar to Figure 3 showing a full astern to full ahead reversal; and

Figures 5 to 8 are diagrammatic views showing modified forms of the invention.

DESCRIPTION—FIGURE 1a

Referring more particularly to Figure 1a, a two-way reverse clutch is indicated generally at 10 and includes 30 an ahead coupling 11 and an astern coupling 12. The two coupling units are selectively energizable to drivingly interconnect a unidirectional engine 14 to a propeller drive shaft 16 of a ship to provide either forward or reverse drive, respectively, through a suitable reverse-and-reduction gear mechanism 18. The coupling units are independently operable by fluid pressure and in a first range of operation are adapted to provide controllable slip of the propeller shaft relative to the driving engine, the speed of the output shaft being substantially 35 proportional to the actuating pressure applied thereto up to a given pressure at which either coupling is normally fully engaged under engine idle speed and load conditions. Further increase in the actuating pressure supplied to either coupling above such a given pressure 40 serves to further increase the speed and torque capacity of the coupling unit.

The two-way reverse clutch 10 includes a driving input assembly common to both the forward and reverse couplings. This driving assembly comprises an engine 50 driven stub shaft 20, a driving spider or disk 21, an annular drive adapter 22, and a driving drum or housing including annular end plates 23, 24 and intermediate members 25, 26, all of which are secured together by suitable means. The intermediate housing members 25 55 and 26 have outer cylindrical portions extending axially from the end plates 23 and 24 and adjacent end portions which extend radially inwardly to provide two flanges in spaced parallel relation to the end plates 23 and 24. The members 23, 24 and 25, 26 thus define two annular recesses for mounting the coupling units 11 and 12.

The coupling units 11 and 12 each includes two axially spaced annular clutch plates 28, 29 and 30, 31, respectively, which are externally splined to the housing members 25 and 26, respectively. These clutch plates carry 65 shoes of suitable frictional material and are adapted to frictionally engage clutch plates 32 and 33, respectively, which are sandwiched therebetween. The clutch plate 32 is internally splined to an ahead drive hub 34 and the clutch plate 33 is similarly splined to a reverse drive hub 35. The ahead drive hub 34 is drivingly connected to a hollow input drive shaft 36 of the reverse-and-reduction gear unit 18. The reverse drive hub 35 is journaled on

the shaft 36 by spaced antifriction bearings 37, 38 and is drivingly connectable to the input drive shaft 36 and the propeller shaft 16 by a conventional reversing-and-reduction gear mechanism within the gear unit 18, a bevel gear of a differential type reversing gear being partially shown at 39. The drive plates 28, 29 and 30, 31 are adapted to be biased into frictional driving engagement with the output drive plates 32 and 33 by the selective inflation of two annular tubes 40 and 41 carried by the drive housing end plates 23 and 24. The axial expansion of the tubes 40 and 41 is transmitted to the several clutch plates through intermediate heat-insulating plates 42 and 43. To insure disengagement of the several clutch plates whenever the tubes 40 and 41 are vented to atmosphere, a plurality of radially and equi-angularly spaced springs 44 are adapted through a plurality of radially extending fingers or spokes 45 to bias the members 42 and 43 out of drive maintaining engagement with the adjacent clutch plates.

The clutch plates 42 and 43 are radially slotted to provide a plurality of radial ribs 42' and 43' which are adapted to thrustably engage the adjacent surface of the drive plates 29 and 31 and define a plurality of radially extending passages therebetween. The inwardly extending flange portions of the housing members 25 and 26 are similarly slotted to provide radial passage-defining ribs 25' and 26' engaging the adjacent surfaces of the drive plates 29 and 30. The drive plates 32 and 33 are also provided with a plurality of radially extending cored passages 32' and 33'. The several passages thus defined intermediate and within the several clutch plate elements open on radially extending passages or ports in the cylindrical portion of the housing members 25 and 26 and upon rotation of the several clutch members these passages serve as radial impellers inducing the rapid flow of cooling air therethrough thus dissipating the heat generated during the clutch engaging process.

Fluid under pressure is supplied to and discharged from the clutch actuating tubes 40 and 41 by way of two flexible air tubes 46 and 47, respectively, which are in turn connected to air supply passages 48 and 49 provided in an air supply tube or shaft 50. The air supply shaft 50 is journaled in and projects from the ends of the hollow input drive shaft 36 of the gear mechanism. The engine end of the air supply tube 50 is drivingly connected to and supported by the input driving assembly of the clutch unit 10, a plate 51 carried by the driving spider 21 and the flange end of the stub shaft 20 being universally connected to the adjacent end of the air tube 50 as indicated at 52. The passages 48 and 49 terminate adjacent the opposite end of the air tube in two axially spaced ports 48' and 49', respectively. These ports register with annular grooves 54 and 55, respectively, which are formed in a fluid seal member 56 journaled on the end of the air tube shaft. The annular grooves 54 and 55 are in turn connected to two inflation pressure supply pipes 101 and 102, respectively.

The engine 14 is provided with an engine driven centrifugal governor 57 of a conventional type having a speed setting shaft 58 rotatable therein with a lever arm 59 secured thereto. The speed setting shaft 58 is adapted upon rotation in a counterclockwise direction to increase the governor speed setting and conditions the governor to regulate the fuel supplied to the engine to maintain engine speed and power output in a well known manner in accordance with the speed setting established thereby. As shown, the speed shaft and the lever 59 are in their engine idle speed maintaining position. The end of the lever 59 distal from the shaft 58 is pivotally connected to one end of a link 60. The opposite end of the link 60 is pivotally connected intermediate the ends of an output lever 61 of a pressure operated motor or actuator device 62.

The actuator unit 62 is connected to one end of a pressure supply pipe 126 and is operable in accordance

with pressure supplied thereto to adjust the speed setting of the governor. Variations in the pressure supplied to the actuator unit above a predetermined minimum effect the reciprocation of a rod or plunger element 64 which is pivotally connected to the actuator output lever intermediate its connection to the link 60 and a stationary pivot 63 at one end of the output lever. Thus an increase in the pressure supplied to the actuator effects counterclockwise speed-increasing movement of the lever 61 about its stationary pivot 63. The pressure responsive movement of the actuator lever 61 is limited between engine idle and maximum speed and load positions defined by stop screws 65 and 65', respectively. The governor speed adjusting linkage intermediate the governor and the speed adjusting actuator is biased in a fuel decreasing direction in opposition to the pressure applied to the actuator unit by suitable spring means, not shown, associated with either the governor or the speed adjusting actuator.

DESCRIPTION—FIGURE 1

In the form of the invention shown in Figure 1, two control stands 66 and 67 are provided for controlling the operation of the two-way reverse clutch and the speed setting of the engine governor. For the purpose of illustration, the control stand 66 is designated as a "pilot house control station" and the control stand 67 is designated as an "engine room control station." As the two control stands are identical in structure and function, corresponding elements of the two stands are hereinafter designated by the same reference numeral, the elements of the engine room stand being differentiated only by the use of a prime (').

The selection of the controlling station is accomplished by the selective operation of a transfer valve 68 including a valve member 68' shiftable between either of two control positions in which the transfer valve is effective to connect the selected control station to a main pressure supply pipe 69 and to deliver pressure control signals therefrom to other elements of the overall control system. The transfer valve member 68' may be selectively shifted between its two control positions by any suitable manual control means, not shown, from a location adjacent either control station. In the position shown, a passage or port *a* provided in the transfer valve member 68' connects the main pressure supply pipe 69 to pipe 70 for supplying pressure fluid to the several control elements of the control stand 66 thus rendering the stand 66 effective to control the operation of the reverse clutch mechanism and of the governor speed adjusting actuator.

A single manually operable maneuvering control lever 71 is secured to a control shaft 72 which is rotatably mounted in the control stand 66 for movement between a neutral position or zone and full speed ahead and astern controlling positions to either side of the neutral position, such positions of the control lever being designated by suitable legends in Figure 1. Two cams 73 and 74 are carried by the shaft 72 and selectively actuate an ahead shift control valve 75, an astern shift control valve 76, and a variable pressure regulator valve 77 in accordance with the direction and degree of movement of the control lever 71 from its neutral zone.

The cam 73 is engaged by two diametrically opposed cam-following valve members 78 and 79 of the two shift control valves 75 and 76. The valve members 78 and 79 normally engage a base circle on the cam 73 when the control lever 71 is in its neutral zone. When in such engagement with the base circle, the valve members 78 and 79 are operative to connect both an ahead shift control pipe 80 and an astern shift control pipe 81 to an exhaust header 82. Operation of the control lever 71 beyond its neutral zone in either direction causes a single lobe A formed on the cam 73 to shift either the valve member 78 or 79, in accordance with the direction of lever movement, to connect either the ahead or astern

shift control pipe 80 or 81, respectively, to the pressure supply pipe 70. The valve member 78 or 79 not shifted by the cam lobe upon such lever movement continues to engage the base circle of the cam 73 and thus continues to exhaust the shift control pipe associated therewith.

The variable pressure regulator valve 77 includes a valve member 83 which is adapted to follow the cam 74. The contour of the cam member 74 is such that when the control lever 71 is in its neutral zone the valve member 83 is operable to connect a clutch inflation and speed control pipe 84 to the exhaust header 82 of the control stand. Movement of the control lever through the indicated end of its neutral zone in an ahead direction causes a lobe B on the cam 74 to actuate the valve member 83 to a control position in which it is effective to deliver an initial pressure signal to the pipe 84 which, if applied to the ahead clutch would be sufficient to equal the biasing action of the springs 44. Further movement of the control lever 71 in the ahead direction between its neutral zone and an intermediate lever position, designated "idle" in Figure 1, causes the cam operated valve member 83 to progressively increase the pressure signal supplied to the pipe 84 up to a pressure which, if applied to the ahead clutch actuating tube 40, would normally be effective to provide full lockup engagement at engine idle speed and load conditions. The lobe B of cam 74 is so contoured that further movement of the control lever 71 through its "idle" position increases the pressure signal delivered to the pipe 84 by the pressure regulator valve to a value which, if applied to the engine governor speed adjusting actuator 62, would equal the biasing action of the spring means associated with the speed adjusting linkage intermediate the governor and actuator. Still further movement of the control lever between its "idle" and "full ahead" positions is effective to progressively increase the pressure signal supplied to the pipe 84 to a maximum pressure which, if applied directly to the ahead clutch and engine speed actuator, would provide for maximum clutch running torque capacity and maximum engine speed. Movement of the control lever 71 between its neutral zone and its "full astern" position causes a second lobe C on the cam 74 to actuate the valve member 83 to supply corresponding pressure signals to the speed and clutch inflation control pipe 84.

In addition to the pressure supply passage *a*, the transfer valve member 68 is provided with passages *b* and *c* which, in the position shown, interconnect the pipes 80 and 81, respectively, to pipes 85 and 86, respectively. The pipes 85 and 86 are connected to opposite ends of a double-acting fluid motor 87 which is operable to control the operative position of a four-way shift selector valve 88. The pipes 85 and 86 are preferably each provided with a conventional flow control type valve indicated diagrammatically at 85' and 86', respectively, consisting of an orifice restricting fluid flow toward the motor 87 and permitting relatively unrestricted flow away from the motor. The transfer valve member 68 is also provided with a passage *d* which, in the position shown, interconnects the speed and inflation control pipe 84 to a pipe 89. The pipe 89 leads to a pilot operated pressure regulating relay valve 90. The pressure regulating valve 90 is adapted to interconnect a speed and inflation control pipe 91 to either the main pressure supply pipe 69 or an engine room exhaust header 92 and supplies an output pressure to the speed and inflation control pipe 91 equal to the pilot signal imposed thereon. Thus when the control lever 71 is in its neutral zone, wherein the pressure regulator valve 77 is operable to vent the pipe 84 to exhaust, the pressure regulating relay valve 90 is similarly operable to connect the pipe 91 to the exhaust header 92. Upon movement of the control lever 71 from its neutral zone in either direction, the pilot pressure imposed on the pressure regulating relay valve 90 causes the regulating relay 90 to supply the same pres-

sure to the speed and inflation control pipe 91 from the main pressure supply.

The four-way selector valve 88 comprises a cylindrical housing or barrel 93 having a bore 94 extending axially therethrough. A valve member 95 is reciprocably mounted within the bore 94 by a plurality of axially spaced O-ring seals 96 which are compressively interposed between and retained within the bore 94 by a plurality of annular port defining rings 97. An inlet port 98 opens on the bore 94 intermediate its ends and is connected to the speed and inflation control line 91. Two outlet ports 99 and 100 open on the bore 94 in flanking relation to the inlet port 98. These outlet ports are connected to an ahead inflation control pipe 101 and an astern inflation control pipe 102, respectively, which are in turn connected to the annular ports 54 and 55, respectively, of the annular rotary seal member 56. The valve barrel 93 is further provided with two exhaust ports 103 and 104 which open on the bore 94 and are spaced axially outwardly of the outlet ports 99 and 100, respectively. These exhaust ports are connected to the engine room exhaust header 92.

The valve member 93 is provided with two axially spaced reduced diameter lands 105 and 106 which separate enlarged diameter land portions 107, 108 and 109 adapted to sealingly engage the port separating O-ring seals 96. A piston member 110 carried by the valve member 95 is reciprocably mounted within the cylinder 87 and defines two double acting expandable chambers 111 and 112 therein which are connected to shift control pipes 85 and 86. The valve member 95 is thus shiftable to an extreme left-hand position in response to fluid pressure applied to the expandable chamber 111 of the cylinder 87 through the shift control pipes 80 and 85, the chamber 112 being simultaneously vented to exhaust through pipes 81, 86 and the astern shift control valve 76. In this left-hand position the reduced diameter land 105 interconnects the pressure inlet port with the ahead inflation outlet port 99 and the astern inflation tube is connected to exhaust by the reduced diameter land 106. Similarly, a shift controlling pressure signal applied to the expandable chamber 112, chamber 111 being vented to exhaust, is operable to shift the valve member to an extreme right-hand position wherein the reduced diameter land 105 serves to vent the ahead clutch and the reduced diameter land 106 interconnects the astern clutch inflation tube to the pressure inlet 98.

When the control lever 71 is in its neutral position, it will be noted that both the expandable chambers 111 and 112 will be vented to the exhaust header 82 through the shift control valve 75 and 76. When the chambers 111 and 112 are thus vented, the valve member 95 is adapted to be centered to the position shown in Figure 1 by a centering spring assembly 113 mounted on the end of the valve barrel 93 opposite the actuator cylinder 87. In this intermediate position, the lands 105 and 106 connect both the ahead and astern inflation pipes 101 and 102 to the exhaust ports 103 and 104, respectively. The centering spring assembly includes a cylindrical casing 114 having two inwardly extending, axially spaced annular shoulders 115 and 116. The shoulder 116 is in the form of a groove-mounted snap ring. The shoulders 115 and 116 serve as abutment stops for two washer members 117 and 118 which slidably embrace a reduced diameter land formed between two axially spaced shoulders 120 and 121 carried by the adjacent end of the valve member. A spring 122 is compressibly interposed between the washer members 117 and 118 and serves to center the valve member by axially aligning the abutment shoulders 115, 120 and 116, 121 of the casing 114 and valve member 95, respectively, in the absence of actuating pressure in either of the expandable chambers 111 and 112.

In the form of the invention shown in Figures 1 and 1a, the speed control pipe 126 is provided with a flow

control valve 126' diagrammatically shown to be of the type having an orifice limiting the flow of actuating fluid to the speed actuator 62 and a check valve permitting unrestricted flow therefrom. The speed control pipe 126 is alternately connectable through a two-way check valve 123 to either the inflation pressure supply pipe 101 or 102. The two-way check valve 123 comprises a cylindrical casing closed at both ends and reciprocably mounting a check valve member 125. Two branch pipes 101' and 102' connect the clutch inflation pipes 101 and 102, respectively, to opposite ends of a check valve casing and the pipe 126 is connected thereto intermediate its ends. The valve member 125 is shiftable in response to the pressure supplied to either of the pipes 101 or 102, the other line being vented to exhaust, to permit the flow of the supplied pressurized fluid to the speed adjusting actuator 62.

DESCRIPTION—FIGURES 2-4

Operations of embodiment of Figures 1 and 1a

The operating characteristics of the form of the invention of Figures 1 and 1a are best shown by the several graphs of Figures 2, 3 and 4 having reference to a specific application thereof to a tug having a diesel engine prime mover rated at 1000 S.H.P at 750 r.p.m.

In Figure 2, curve I indicates the interrelationship between the propeller speed, in direct proportion to the engine speed, and the pressure signal supplied to the inflation and speed control pipe 84 by the control stand pressure regulator 77 upon movement of the control lever between its neutral and either its full ahead or astern positions. Curve II represents the minimum clutch inflation pressure required to maintain a given output shaft speed when the tug is running free, without tow, and thus represents a minimum torque condition. Curve III represents the minimum clutch inflation pressure required to maintain a given output shaft speed when the tug is driving against a dock thus simulating a torque condition corresponding to that required to initiate a tow. Above the clutch slip range curves II and III further define the inflation pressures at which the speed of the output shaft of the clutch corresponds to that of the clutch input shaft, the creep therebetween being less than one revolution for thirty minutes of operation. As indicated, the pressure differential between curves I and II or III represents additional available clutch torque capacity for acceleration of the tug and its tow. This excess torque capacity insures against any prolonged periods of clutch slippage under high speed and torque conditions.

Assuming the engine to be operating at idle speed with the control lever 71 of the controlling station in its neutral position or zone, both the ahead and the astern clutches are de-energized since the shift selector valve member 95 is in its neutral position venting both inflation tubes 40 and 41 and the governor speed setting actuator 62 to exhaust. Initial movement of the control lever from its neutral zone actuates one of the shift control valves 75 or 76 to supply actuating pressure to one end of the actuating cylinder 87 thereby causing the piston 110 to shift the selector valve member 95 to one of its two shift controlling positions in accordance with the direction of control lever movement. Such initial movement of the control lever also shifts the regulating valve member 83 to close the connection between the exhaust header 82 and the inflation and speed control pipe 84 and to provide an initial supply of pressurized fluid of approximately three pounds per square inch to the latter pipe. As duplicated by the pressure regulating relay valve 90 and supplied to either of the clutch actuating tubes 40 or 41 through the shifted selector valve 83, this initial pressure of three pounds is sufficient to overcome the biasing action of the springs 44 and initiates frictional driving engagement between the several plates of the corresponding clutch unit thereby initiating rotation

of the propeller shaft. Further advancement of the control lever 71 in either its ahead or astern control slip ranges serves to increase the actuating pressure supplied to the oncoming clutch thereby decreasing the slip and increasing the torque transmitted between the driving and driven members. Thus the speed of the propeller shaft may be effectively controlled by the operator-selected position of the control lever to hold the tug against a tidal or river current or to slowly and smoothly initiate propulsion of the tug and its tow. The actuating pressure supplied to the oncoming clutch will generally be effective to shift the two-way check valve 123 to supply such pressure to the speed control pipe 126. However, when the control lever is in either of its clutch slip zones, such supplied pressure will be ineffective to actuate an adjustment of the governor speed setting.

As the control 71 is advanced toward its idle position, the inflation pressure supplied by the regulator valve 77 approaches a value of approximately 10 pounds per square inch which is the inflation pressure required to provide full engagement between the driving and driven members of the clutch unit under engine idle maximum torque conditions. Further movement of the control lever into its engine idle position causes the regulator valve 77 to increase the pressure supplied to the inflation and speed control line 84 to a value of approximately 12½ p.s.i. When duplicated by the relay regulating valve 90 and supplied through the shifted selector valve to either of the inflation control lines 101 or 102 and therefrom through the two-way check valve 123 to the speed control line 126, this pressure is effective to counter-balance the spring means biasing the governor speed adjusting linkage to its idle position. Movement of the control lever between its idle and full speed ahead or astern positions varies the magnitude of the pressure signal supplied to the line 84 by the regulator 77 in proportion to the degree of movement of the control lever. Thus, for any given position of the control lever in either of its idle-to-full speed zones, a pressure signal is provided which provides a given torque capacity for the driving coupling and effects the adjustment of the governor speed setting to provide a given engine speed and thereby a given propeller shaft speed.

In actual practice, the operation of the control lever 71 will generally not be accomplished slowly and smoothly enough to increase the pressure signal and thereby propeller speed as per curve I of Figure 2.

Normally the operator will actuate the control 71 almost instantaneously to a position corresponding to the desired propeller shaft speed. Assuming an almost instantaneous movement of the control lever 71 from its neutral control zone to a second position within its ahead engine speed controlling zone, such a movement of the lever causes the ahead shift control valve 75 to supply a pilot signal to the cylinder 87 thereby actuating the valve member 95 to its ahead drive establishing position. Such lever movement also rapidly actuates the regulator valve member 83 to a position wherein it is effective to supply a pilot pressure signal corresponding to the second position of the lever 71, by way of example, 50 pounds per square inch. This pressure signal is applied to and duplicated by the pilot operated pressure regulating relay valve 90. The flow of the pressurized fluid emanating from the regulating relay valve 90 through the selector valve 83 to the ahead clutch actuating tube 40 and through the two-way check valve 123 to the governor speed actuator 62 is retarded or throttled by the orifice of the flow control check valve 91'. The flow of the supplied actuating pressure to the governor speed actuator 62 is further retarded by the flow control valve 126'. It will thus be seen that the flow control valve 91' controls the inflation of the clutches to provide relatively smooth progressive engagement under such operating conditions and cooperates with the flow control valve 126' to retard advance-

ment of the engine speed governor setting during clutch engagement until a clutch pressure has been attained sufficient to carry the desired propeller speed and load; the flow control valve 126 preventing engine acceleration and therefore engine overspeed prior to proper clutch inflation.

Advancing the control lever further to its full ahead position, the several pressure regulators supply pilot and clutch actuating pressures of 60 p.s.i. further increasing the torque capacity of the ahead clutch and adjusting the 10 governor speed setting to its maximum speed and load limiting condition.

As best seen by the graphs of Figures 3 and 4, it is possible in the illustrative application of the invention to achieve a reversal of propeller drive from full speed ahead to full speed astern, or vice versa, within a period of five seconds without undue heating and wear of the several clutch elements. In Figure 3 curve IV represents engine speed per unit time and curve VI represents the speed and direction of the propeller shaft per unit time 20 during such a high speed reversal. Curves V and VII indicate corresponding engine and propeller speed curves and the minimum time for effecting such a high speed reversal with a comparable electric drive for the same tug. In Figure 4 the engine speed curve IV is duplicated during the full speed astern to full speed ahead reversal of the propeller shaft, the speed of which is indicated by the curve VIII. The broken line curve IX in this figure indicates the free wheeling of the propeller shaft which would occur upon complete disengagement of the astern driving clutch 12 if engagement of the ahead clutch were not almost immediately initiated to effect a braking action on the astern rotation of the propeller drive shaft system.

The operation of the control system during such high speed maneuvering reversals is outlined briefly below. Movement of the control lever 71 from its full ahead position to its full astern position vents the valve shift actuator chamber 111 through the ahead shift control valve 75 to the exhaust header 82. Opening of the check valve of the flow control valve assembly 85' permits this venting of the chamber 111 to be relatively unrestricted. However, the pilot pressure from the astern shift control valve 76 is restricted in its application to the expandable chamber 112 by the orifice of the flow control valve 86'. Consequently, the centering spring assembly 113 initially actuates the valve member to its centered position, wherein it vents the ahead clutch and the governor speed adjusting actuator to the exhaust header 92, until the astern shift pilot pressure is sufficient in the expandable chamber 112 to shift the valve member 95 to its astern shift controlling position wherein the land 106 interconnects the astern inflation and speed control pipe 102 to the regulated pressure supply of the relay valve 90. During the rapid movement of the control lever 71 from its full ahead to full astern positions the inflation and speed controlling pilot signal emanating from the pressure regulator valve 77 is reduced until the control lever passes through its neutral zone wherein the inflation and speed control pilot line 84 are connected to the exhaust header 82 and is subsequently increased until it again reaches its full engine speed value. However, it should be noted that this pilot inflation and speed controlling signal, as duplicated by the relay valve 90, is not applied to the oncoming astern clutch until the initial centering of the shift selector valve 95 has first vented the ahead clutch inflation tube and the governor speed actuator thereby substantially disengaging the ahead clutch and reducing the engine governor to its idle speed setting. This is best seen from curves VI, VIII and IX which show the propeller shaft speed curves VI and VIII tending to follow the free wheeling curve IX until the engine speed has been reduced substantially to its idle position.

By proper selection or adjustment of the orifice size of the flow control valve assembly 86', as the engine approaches its idle speed the shift selector valve member

95 is shifted to its astern controlling position thereby initiating the flow of actuating pressure to the oncoming astern clutch. This flow of pressurized fluid to the oncoming clutch is of course restricted by the flow control valve assembly 91'. Hence, the astern clutch is smoothly and progressively energized throughout its clutch slip range to initially brake the ahead rotation of the propeller shaft system down to zero speed and then to reverse and drive the propeller with increasing speed and torque. As the astern clutch becomes effectively fully engaged at engine idle speed, the increasing pressure is applied to the governor speed actuator through the two-way check valve 123 and serves to progressively increase the governor speed setting up to its full speed and power maintaining position.

A reversal from full speed astern to full speed ahead is similarly effected by the embodiment of the invention of Figures 1 and 1a, as shown by the graph of Figure 4, and consequently need not be discussed in detail. However, it will be noted that the propeller shaft and engine speed curves IV and VIII coincide between the point at which the oncoming ahead clutch is fully engaged and the full speed ahead condition.

From the foregoing description of the operation of the 25 form of the invention of Figures 1 and 1a it will be seen that the four-way shift selector valve 88 provides a positive mechanical interlock preventing the simultaneous supply of actuating pressure to the actuating tubes of both the ahead and astern clutches and when utilized 30 with the flow control valves 85' and 86' insures substantial disengagement of the offgoing clutch before engagement of the oncoming clutch is initiated. This latter feature, when taken in conjunction with the two-way check valve 123, serves to provide a positive pneumatic 35 interlock between clutch inflation and engine speed and is effective to reduce engine speed during reverse maneuvering operations thereby preventing excessive heating of the clutches. This interlocking arrangement also prevents stalling or overloading the engine during such reversing 40 operations since the clutch torque capacity at any particular pressure setting within the clutch-slip, engine idle range is insufficient to stall the idling engine. After initial full clutch engagement, the available clutch torque capacity at any particular pressure setting is substantially 45 greater than the available engine torque. It should also be noted that since clutch inflation pressure is used to control the governor actuator through the two-way check valve, this arrangement will automatically result in a 50 reduction in engine speed in the event of a low clutch inflation pressure which might otherwise permit destructive clutch slippage.

DESCRIPTION—FIGURE 5

In the form of the invention of Figure 5, the drive intermediate the engine and the propeller shaft, the engine 55 governor speed adjusting mechanism, and the remote control stations, as well as other component elements, are identical with those shown and described with reference to Figures 1 and 1a. Such components are therefore 60 represented by the same reference numerals in Figure 5 although being shown somewhat more diagrammatically.

In this form of the invention, the pilot pressure actuation of the four-way selector valve 88 by the control lever operation of the shift control valves 75 and 76 is positively 65 interlocked by means of suitable clutch inflation pressure actuated relays 130 and 131 to assure complete disengagement of one clutch before the other clutch is actuated to drivingly connect the propeller shaft to the engine. This positive interlocking of the selector valve shifting 70 is utilized in place of the controlled time delay which is introduced by the flow control valves 85' and 86' of the first embodiment and momentarily maintains the selector valve in its neutral position during the reversal cycle.

The inflation pressure actuated relays 130 and 131 are 75 associated with and adapted to control the flow of pres-

surized fluid to the opposite ends of the shift selector valve actuating cylinder 87 through the pipes 85 and 86, respectively. The valve members of these two relays are normally spring biased to a position indicated by the broken lines *e* and *f*, respectively, to provide a through passage between the separate ends of the pipes 85 and 86, respectively. To assure complete disengagement of either the ahead or astern driving clutch before the other clutch is energized to pick up torque, the pressure actuating means of the ahead shift controlling relay 130 is connected to the astern speed and inflation control pipe 102 by a pipe 102' and the pressure actuating means of the astern shift control relay 131 is similarly connected to the ahead inflation and speed control pipe 101 by the pipe 101'. Hence, when an inflation and speed controlling pressure is supplied to the pipe 101 sufficient to initiate engagement of the ahead clutch, this signal is applied to the astern shift control relay 131 and is operative to actuate the valve member thereof to a second control position indicated by the broken line *f*' to connect the portion of the pipe 86 intermediate the actuator cylinder 87 and the relay to the engine room exhaust header 92. An engagement initiating inflation pressure supplied to the pipe 102 is similarly effective on the ahead shift controlling relay to connect the expansible chamber 111 of the shift actuator 87 to the exhaust header 92 as indicated by the broken line *e*'. Thus when the control lever is reversed as in fast maneuvering, shifting of the selector valve to effect a reversal is prevented until the pressure in the engaged clutch is reduced to approximately its minimum inflation pressure.

It should be noted that the interlocking relay valves 130 and 131 delay pressure supply to the oncoming clutch in proportion to the opposite clutch inflation pressure, but only during reverse maneuvering operation. Direct response is still attainable whenever the control lever 71 is moved from its neutral position, with both clutches disengaged, to either an ahead or an astern drive controlling position.

To compensate for the somewhat delayed energization of the oncoming clutch during rapid maneuvering operation of this system, relative to that provided by the first form of the invention, a relay valve 135 is provided which is operative to control a passage or pipe 136 bypassing the flow control valve 91'. Whenever the pressure in the portion of the pipe 91 between the flow control valve 91' and the selector valve is above the minimum pressure required for full clutch engagement, this pressure is applied to the relay valve 135 by branch pipe 136' and is operative to shift the relay valve member between a closed position, indicated by the broken lines at *g*', to an open bypassing position, indicated at *g*. This permits a rapid and relatively unrestricted build-up of the inflation pressure applied to the oncoming clutch and to the governor speed adjusting actuator through the pipe 126 and the flow control valve 126' and thus provides for a more rapid advance of the engine governor speed setting shaft between its idle and maximum speed and load positions.

As a further refinement of the form of the invention shown in Figure 5, two flow control valves 132 and 133 are interposed in the pipes 102" and 101", respectively. Such valves introduce a time delay in the build-up of interlocking pressures applied to the relay valves 130 and 131, respectively, while permitting relatively unrestricted venting of such interlocking pressures from the relay valves. By properly proportioning the orifices of such flow control valves, immediate response or shifting of the selector valve is permitted without interlocking when the control lever is rapidly actuated between its idle ahead and idle astern positions.

DESCRIPTION—FIGURE 6

In the embodiment of the invention shown in Figure 6, a control lever 140 of a pilot house control stand 141 is

operatively connected to a rotary actuator device 144 by suitable hydraulic, electrical or mechanical means indicated at 142. The rotary actuator 144 includes a rotary output shaft 145 and is adapted to impart an angular movement thereto corresponding to the angular movement of the control lever 141. The shaft 145 is drivingly connected to a control shaft 146 of an engine room control stand 147 which is basically similar to the control stands 66 and 67 of the preceding embodiments. The control shaft 146 is also adapted to be manually operated by a control lever 148 mounted thereon.

The control stand 147 is connected to a suitable source of pressurized fluid by a pipe 149 and is adapted upon movement of either control lever 140 or 148 in an ahead direction to deliver an ahead-shift pilot signal to a pipe 150 or upon movement of either control lever in an astern direction to deliver an astern shift pilot signal to a pipe 151. The control stand 147 is also adapted to deliver a variable inflation and speed controlling pressure signal to a pipe 152, such signal being proportional to the angular movement of either control lever from its neutral position.

A flow control valve 153 interposed in the pipe 152 corresponds to the flow control valves 91' of the preceding embodiments. The pipe 152 is connected by two branch pipes 154 and 155 to the inlet ports of two pressure operated, three-way relay valves 156 and 157, respectively, which serve as ahead and astern shift control valves replacing the single four-way, spring centered and pressure actuated shift valve 88 of the preceding forms of the invention. The relay valves 156 and 157 are of conventional design and have valve members which are normally spring biased to provide exhaust connections *m*' and *n*', respectively, between the clutch inflation and speed control pipes 101 and 102, respectively, and the engine room exhaust header 92. Each relay valve member is shiftable to a second operative position in response to a shift controlling pilot signal applied thereto wherein pressure supplying connections *m* and *n* are established between the pipes 154 and 101 and between the pipes 155 and 102, respectively.

The application of the shift controlling pilot signals from the pipes 150 and 151 to the shift control relay valves 156 and 157, respectively, is controlled by the interlocking action of two inflation pressure actuated relay valves 158 and 159 corresponding to the interlocking relays 130 and 131 of the embodiment of Figure 5. The valve members of the interlocking relay valves 158 and 159 are normally spring biased to a first position to provide through passages indicated *o* and *p*, respectively, between the ahead shift signal pipe 150 and a pipe 150' leading to the pressure sensing unit of the shift control relay valve 156 and between the astern shift pipe 151 and a pipe 151' leading to the pressure sensing unit of the astern shift control relay valve 157, respectively. The valve member of the interlocking relay valve 158 is shiftable to a second operative position *o*' venting the pipe 150' to the exhaust header 92 in response to astern inflation pressure applied thereto from the pipes 102 and 102' through a pipe 102". The valve member of the interlocking relay valve 159 is similarly shiftable to a second position venting the pipe 151' to exhaust whenever ahead inflation pressure is supplied thereto from the pipes 101 and 101' through an interconnecting pipe 101".

With the exception of the independent operation of the shift controlling relay valves 156 and 157 and the omission of the flow control valves 132 and 133 and the flow control bypassing relay valve 135, the operation of the embodiment of Figure 6 is essentially the same as that of the form of the invention of Figure 5.

DESCRIPTION—FIGURE 7

It will be noted that with the embodiments of the invention of Figures 1 and 1a, 5, and 6, when the con-

control lever is moved from or through its neutral position, there will necessarily be a lag period as the pressure applied to the oncoming clutch builds up to overcome the action of the spring 44; before clutch engagement is initiated to pick up the propeller load and start accelerating the masses involved in the propeller drive system. Since the flow of inflation pressure to the oncoming clutch through the flow control valves 91' or 153 is proportional to the pressure supplied, such a lag will be proportionally much longer when the movement of the control lever is limited to a relatively low speed position. Such a lag may be overcome by the operator moving the control handle to a speed position beyond the speed at which he desires to operate with subsequent return of the handle to its desired position. Such operation provides a momentary boost in the initial inflation pressure applied through the flow control valve to the oncoming clutch thus shortening the delay in initial clutch engagement. Such a momentary pressure boost may also be provided automatically with the supplementary control mechanism shown in Figure 7.

The supplementary control of Figure 7, comprises a pressure operated relay valve 164 which is operable to control the flow of the inflation and speed controlling pressure signal either in the remote control pipe 89 or in the engine room pipe 91 or 152 of the several preceding embodiments. The relay valve 164 has a valve member which is normally shiftable by the shift controlling pilot signal from either the ahead or astern shift control pipe 85 or 86, respectively, to provide a through connection *q*, between the ends of the pipe 89 separated thereby. The ahead and astern shift signal supplying pipes 85 and 86 are connected to the opposite ends of a two-way or double check valve 160, similar to 123, through branch passages 85" and 86", respectively. The valve member of the check valve 160 is shiftable, in response to the oncoming shift controlling signal in one pipe and to the venting of the other, to supply the oncoming shift controlling signal to a pipe 161 connected to the check valve 160 intermediate its ends. The pipe 161 is connected through a flow control valve 161' to the pressure sensing end of the relay valve 164 and to a chamber 165 of a predetermined volume. When the pressure applied to the pressure sensing end of the relay valve drops below a predetermined amount, e.g. 40 p.s.i., the valve member thereof is adapted to be shifted to a second position *q'* connecting the outlet end of the pipe 89 to a pipe 162. The pipe 162 is in turn connected to the pipe 161 by a pressure regulator valve 163. The regulator valve 163 is adapted to convert the shift controlling signal, e.g. 60 p.s.i., to a predetermined constant pressure, e.g. 30 p.s.i., and to supply such constant pressure to the pipe 162.

The operation of the supplementary control of Figure 7 is as follows, assuming the control stand lever to be actuated from an ahead driving position to an astern driving position. As the control lever passes through its neutral position, the ahead shift control pipe 85 is vented to exhaust through the ahead shift control valve 75. This venting of the line 85 also vents the pipes 85" and 161, the relay valve 164, and the chamber 165 to exhaust prior to the shifting of the two-way check valve 160 in response to the build-up of the astern shift pilot signal supplied thereto above the venting pressure in the ahead shift pipe. This effects a momentary reduction in the pressure applied to the sensing unit of the relay valve 164 and within the chamber 165 below 40 p.s.i. Consequently, the valve member of the relay 164 is shifted to its second control position wherein the pipe 162 is connected to the outlet end of the pipe 89 thus supplying the constant 30 p.s.i. pressure from the pressure regulator valve 163 to the inflation tube of the oncoming astern clutch. Normal inflation and speed control is restored by the relay valve 164 whenever the pressure in the pipe 161 intermediate the flow control

valve 161' and the chamber 165 again exceeds 40 p.s.i. The timing for effecting such restoration of normal inflation and speed control is accomplished by properly relating the volume of the chamber 165 to the size of the orifice of the flow control valve 161'.

DESCRIPTION—FIGURE 8

The form of the invention shown in Figure 8 is particularly adapted for use in those applications requiring high degrees of control and responsiveness such as with multi-engine installations having a single output shaft.

The drive intermediate the engine and propeller shaft is identical with that shown in Figure 1a, the ahead and astern clutch units respectively being adapted to reverse the driving relation between the engine driven shaft 20 and the input driving shaft 36 of the reverse gear unit 18. As in the embodiments of Figures 1 and 5, the selective energizing and deenergizing of the astern and ahead clutch units are controlled by the operation of a four-way pilot operated shift valve 88 which is shiftable to either of two shift controlling positions in response to the selective application of shift controlling pressure signals delivered to the ends of the valve actuating cylinder 87 associated therewith or to a centered neutral position provided by the spring centering assembly 113.

This control system features the coordination of clutch engagement with the propeller shaft speed during operation in the clutch slip speed ranges to provide a relatively fast rate of response during reversals from one slip range to the other. For operation above the clutch slip speed ranges this control system is adapted to apply a single high pressure to the inflation tube of the selected clutch which is sufficient to maintain full clutch engagement under all engine load and speed conditions between idle and full speed ahead or astern. Consequently, the speed controlling signal is necessarily regulated and supplied to the governor speed adjusting actuator separately, although coordinated with, the clutch inflation controlling signal. This requires the elimination of the speed controlling two-way check valve connection intermediate the clutch inflation lines 101 and 102 and the speed actuator of the preceding embodiments. It will be noted that the governor, the governor speed adjusting actuator and the interconnecting linkages are shown diagrammatically to be similar to those of the first and second forms of the invention and are therefore designated by the same reference numerals.

The pressure supply for the instant system includes an air receiver 201 which is connectable through a check-valve-controlled pipe 200 to a suitable air compressor. The receiver is connected to and supplies a constant actuating pressure to the propulsion control system through a pipe 202, flow through the pipe 202 being controlled by a combined filter and pressure regulator unit indicated at 202A and a manually operable shut-off valve 202B. A branch pipe 202' leading from the pressure supply pipe 202 is adapted to supply pressure through a flow control valve 244 and a pressure operated relay valve 231 to a pipe 232 leading to the pressure inlet 98 of the four-way shift control valve 88 for clutch inflation during idle to full speed ahead or astern operation. A second branch 202" from the pressure supply pipe 202 is controllable by the selective actuation of a valve member 203' of a transfer valve assembly 203 to alternatively supply control pressure to either a pipe 204 leading to a pilot house control stand 210 when the valve member is in its position indicated by the broken lines at *a* or to a pipe 204' leading to a similar engine room control stand, not shown, when the valve member is in its broken-line-indicated position *a'*.

As shown diagrammatically, the control stand 210 includes a manually operable lever 211 which is secured to a control camshaft 212 rotatably mounted in the stand. The camshaft 212 is provided with four cams axially spaced thereon and indicated at 213, 214, 215

and 216. The cam 216 is provided with a first control lobe G which is adapted to actuate a valve member 205 of a shutoff valve 206 to a closed position whenever the control lever 211 is within its neutral zone. Actuation of the control lever from its neutral zone permits the valve member 205 to be shifted to a second position wherein the pressure supply header 204d is connected to the pipe 204 through an interconnecting branch pipe 204a thus supplying actuating pressure to the several other control elements of the stand. A pressure operated relay valve 207 responsive to the pressure in the supply header 204d is adapted to provide a direct connection between the header 204d and the pressure supply pipe 204 through a branch pipe 204c whenever the pressure in the supply header 204d is in excess of a predetermined pressure. With this interlocking pressure supply arrangement, a momentary loss of control stand operating pressure, which would otherwise occur each time the control lever is actuated through its neutral position, is prevented. It will be appreciated that this feature improves the overall responsiveness of the system.

The cam 213 is similar in function and configuration to the cam 73 of Figure 1, having a shift controlling lobe D thereon adapted to alternatively actuate the valve member 218 of an ahead shift control valve 217 to a position supplying a shift actuating pressure to the line 80 from the header 104d or to actuate the valve member 221 of an astern shift control valve 220 to a position supplying an astern shift signal to the line 81 from the header 204d. When the ahead and the astern shift valve members are not in actuating contact with the lobe D, as when the control lever is in its neutral position, they are returnable to a position interconnecting both of the shift control pipes 80 and 81 to the pilot house exhaust header 219. As in the embodiment of Figure 1, the pipes 80 and 81 are connectable by the transfer valve member 203', when in the positions indicated in broken lines at c and b, to the pipes 85 and 86, respectively, which are connected to the opposite ends of the actuator cylinder 87 for shifting the four-way valve.

The cam 215 serves to control the slip engagement of the energized clutch when the control lever 211 is actuated to a control position within either of the indicated ahead or astern slip ranges. The configuration of the cam 215 is such as to actuate a valve member 223 of a pressure regulator 222 to interconnect the pressure supply header 204d to a pipe 224 and to supply a variable pressure thereto proportional to the degree of movement of the control lever and of the valve member 223 from their shown neutral positions wherein the valve member 223 engages an arcuate surface of minimum radius on the cam 215 and is adapted to connect the pipe 224 to the exhaust header 219. The arcuate surface defining the neutral zone on the cam 215 is flanked by two rises of increasing radius F and F' which are adapted to progressively shift the valve member 223 to increase the regulated pressure supplied to the pipe 224 throughout the clutch slip ranges for ahead and astern operation, respectively. The two cam rises F and F' terminate in a cylindrical surface which extends therebetween on the side of the cam opposite the neutral zone and defines the maximum opening of the valve member 223 to provide the pressure required for full clutch engagement under idle speed and load conditions. The opposite end of the pipe 224 is connected to a pressure regulator relay valve 225 of the so-called computing type having an output pressure controlled in accordance with the differential between several pressure control signals imposed thereon. The pressure signal delivered by the pipe 224 to the relay valve 225 provides a first control signal or "set point" for controlling the pressure regulation thereof in accordance with the desired speed of the output shaft. A second control signal or "set point" for the

5 differential computing relay 225 is provided by an air tachometer 227 through an interconnecting pipe 228. The tachometer 227 is drivingly connected to the propeller shaft 16, as indicated at 226, and the pressure signal generated thereby is of course proportional to the speed of the propeller shaft.

10 A pressure regulator valve 233 interposed in a branch 204b of the pressure supply pipe 204 reduces the constant pressure supplied thereto to a lower constant output pressure equal to that pressure required for full clutch engagement under engine idle speed and load conditions and this reduced pressure is supplied to the differential relay valve 225. As indicated above, the differential relay valve is adapted to regulate the flow of fluid pressure from the branch 204b to an outlet pipe 229 in accordance with the "set point" pressures imposed thereon. The pipe 229 is connectable through an inflation pressure controlled safety relay valve 230 and the inflation pressure supply controlling relay 231 to the inlet pipe 232 of the four-way valve. The inflation pressure sensing unit of the safety relay valve 230 is connected to the pipe 232 by a branch pipe 232'. This safety relay valve insures the isolation of the relatively low pressure differential relay valve 225 from the high inflation pressure which is supplied through the relay valve 231 under idle to full speed ahead or astern operating conditions.

15 The operation of the differential relay 225 is such that a slip speed indicating signal of a given magnitude supplied to the pipe 224 when the output shaft 16 is at rest or rotating at a substantially lower speed causes the relatively unrestricted flow of the pressurized fluid supplied thereto to the energized or oncoming clutch. This imposes a relatively high initial or starting torque capacity on the oncoming clutch with resultant rapid acceleration of the output shaft 16. However, as the speed of the output shaft approaches the speed indicated by the control stand regulated "set point" pressure in the pipe 224, the increasing "set point" pressure supplied to the relay 225 by the air tachometer 227 causes the differential relay to reduce the pressure supplied to the energized clutch by venting a portion of the pressure previously supplied to the pipe 229 to the exhaust header 92 until the inflation pressure required for the desired speed maintaining slip-page is reached. Should the control stand "set point" pressure in the pipe 224 be reduced to a pressure indicating a desired speed less than that of the output shaft, the computing relay will similarly vent a portion of the clutch inflation pressure to the exhaust header below that required for the desired speed until the output shaft speed indicating "set point" again matches the "set point" pressure in the pipe 224.

20 A second control stand mounted pressure regulator valve 234 is adapted to supply a speed controlling pressure signal to a pipe 236 and therefrom to the governor speed actuator 67 in accordance with the movement of the control lever 211 between its idle and full speed ahead and astern control positions; a pressure regulating valve member 235 of the regulator valve 234 being maintained in thrust engagement with the surface of the cam 214 and actuated thereby. The surface of the cam 214 is formed on a single radius intermediate its ahead and astern engine idle speed controlling positions and maintains the valve member 235 in a position venting the outlet pipe 236 to the exhaust header 219 throughout the neutral and slip range of movement of the cam 214 and the lever 211. At its engine idle speed controlling positions, the cam surface is provided with an initial rise adapted to actuate the valve member 235 to an initial pressure supplying position wherein the minimum pressure required to counterbalance the engine idle maintaining means of the governor 57 and actuator 67 is supplied to the pipe 236. In its idle-to-full speed ahead and astern controlling sectors the surfaces of the cam 214 are provided with rises as indicated at E and E', respectively, which are adapted to shift the valve member 235 to

progressively increase the speed control pressure signal supplied to the pipe 236 in accordance with the angular movement of the control lever in either speed increasing direction.

The flow of the speed controlling pressure signal to the actuator 67 through the pipe 236 is controlled by the orifice of a flow control type check valve 237 and a pressure operated relay valve 238. The relay valve 238 is operable to provide a through connection between the ends of the pipe 236 separated thereby in response to a predetermined pressure signal supplied to the pressure sensing unit thereof. In the absence of such a predetermined pressure applied to its pressure sensing unit, the relay valve 238 is adapted to vent the governor speed actuator 67 to the engine room exhaust header 92.

The cam 216 is provided with a second lobe thereon diametrically opposite end lobe G and extends arcuately thereof through an angular sector substantially equal to that subtended by the slip and neutral zones of the control lever. When the lever 211 is in its neutral or either of its slip zones, the lobe H thrustably engages and actuates a valve member 239 of a shutoff valve 240 to a position wherein it provides a connection between a pipe 204e and the control station exhaust header 219. When the control lever 211 is shifted to either of its idle speed controlling positions, the lobe H no longer engages the valve member 239 which is returnable to a position interconnecting the pressure supply header 204d to the pipe 204e. The pressure thus supplied to the pipe 204e is delivered through branch pipes 204f and 204g connected thereto to the pressure sensing units of the inflation controlling relay 231 and 238, respectively. The flow of pressure fluid to the relays through the branch pipes 204f and 204g is controlled by flow control valves 241 and 242, respectively, interposed therein. By proper selection of orifice size for the flow control valves 241 and 242 and the valve actuating pressures for the relays 231 and 238, the relay valve 231 will first be actuated to supply full inflation pressure to the engaged clutch prior to the actuation of the relay valve 238 to supply speed increasing pressure to the governor speed actuator.

Operation of embodiment of Figure 8

The operation of the embodiment of the invention of Figure 8 will generally be apparent from the foregoing description. However, such operation is outlined briefly below.

Assume the control lever is actuated from its neutral zone to an astern slip position. This initial movement of the control lever causes the valve member 205 to be shifted to its opened position supplying pressure to the control stand supply header 204d. The astern shift valve member 221 has similarly been shifted to its opened position and the shift controlling pressure signal thus supplied to the shift valve actuator 87 causes that valve to be shifted to its astern controlling position. The pressure signal supplied to the differential computing relay 225 by the pressure regulator valve 222 in accordance with the adjusted position of the control lever and by the air tachometer 227 in accordance with the propeller speed causes the differential relay to supply the idle speed full engagement inflation pressure from the pressure regulator valve 233 to the astern clutch through the pipes 229, 232" and 102 as controlled by the safety relay valve 230, the inflation control valve 231 and the shift control valve 88. As the speed of the output propeller shaft approaches the desired speed indicated by the adjusted position of the control lever the differential relay valve reduces the astern clutch inflation pressure to provide the desired propeller shaft speed.

If the control lever is now actuated to a position within its astern engine speed controlling sector, the resultant increase in the pressure signal in pipe 224 causes the differential relay 225 to initially supply the full output pressure of the pressure regulator 233 to the

astern clutch. Since the flow of fluid pressure to the inflation controlling relay 231 and the speed controlling relay 238 is retarded by the flow control valves 241 and 242, respectively, the pressure supplied through the differential relay initiates full astern clutch engagement prior to the actuation of the relay valve 231 to provide full supply pressure to the engaged clutch and the subsequent actuation of the relay valve 238 to supply the speed controlling signal to the governor speed actuator.

In accomplishing a high speed reversal from the now established astern speed to full speed ahead, the control lever is quickly actuated by the operator to its full speed ahead position. The movement of the control lever 211 and the several cams through their astern slip ranges causes the valve 240 to vent the pipe 204e to exhaust. This rapidly exhausts the pressure sensing units of the relay valves 231 and 238 through the flow control valves 241 and 242 with the consequential venting of the governor speed actuator to reduce the engine speed to idle and the re-establishing of the low pressure connection between the pipes 229 and 232.

As the several cams pass through their neutral positions and into the ahead slip range the astern shift valve 220 vents the corresponding end of the shift valve actuator to exhaust to permit the oncoming shift controlling signal provided by the valve 217 to actuate the shift valve to its ahead controlling position. As the control lever is rapidly advanced to its full speed ahead position, the pressure signals imposed on the differential computing relay will be such as to initially apply idle speed engaging pressure of the regulator valve 233 to the ahead clutch to effect the engagement thereof prior to the actuation of the relay valve 231 to provide full supply pressure to the engaged clutch and the subsequent actuation of the relay valve 238 to permit adjustment of the actuator 67 to advance the governor to its maximum speed and load maintaining setting.

The preferred embodiments of the invention have been described in detail for the purpose of explaining the several principles, objects, advantages and features of the invention and the best known means of practicing the invention. It is to be understood, however, that the invention is not to be considered as limited by this description. Many modifications may be made by the exercise of skill in the art without departing from the scope of the principles of the invention as defined in the following claims.

We claim:

1. A drive control apparatus including two couplings independently operable by fluid under pressure to provide alternative driving connections between a load and a prime mover of torque capacity substantially proportional to the pressure of such fluid and operable upon release of such fluid under pressure to disconnect said load from said prime mover, a power control motor operable by fluid under pressure to adjust the speed of said prime mover between minimum and maximum limits in proportion to the pressure of such fluid, a first valve means operable to selectively supply and release fluid under pressure to and from either one of said couplings, a second valve means operable to supply fluid under pressure to operate said motor, a control device operable to regulate the pressure of fluid supplied through said first and second valve means to said couplings and motor and including a control element movable from a no-pressure supply position to either of two full pressure supply positions, and means for controlling operation of said first and second valve means to control the supply of fluid under pressure to and its release from each of said couplings and said motor in accordance with movement of said control element to and from its no-pressure supply position.
2. An apparatus for controlling two couplings independently operable by fluid under pressure to provide a driving connection between a load and a prime mover

of torque capacity substantially proportional to the pressure of such fluid and operable upon release of such fluid under pressure to disconnect said load from said prime mover and for also controlling a power control motor operable by fluid under pressure above a predetermined pressure to adjust the speed of said prime mover in proportion to the pressure of such fluid, comprising in combination with said couplings and motor, a first valve means operable to selectively supply fluid under pressure to either one of said couplings and at the same time release fluid under pressure from the other coupling, a second valve means operable in response to the supply of fluid under pressure to either one of said couplings to provide a connection between said one coupling and said motor to thereby supply such fluid under pressure to operate said motor, a control device operable to regulate the pressure of fluid supplied through said first and second valve means to said couplings and motor, said control device including a control element movable from a no-pressure supply position to either of two full pressure supply positions and means for controlling operation of said first valve means to control the supply of fluid under pressure to and its release from each of said couplings in accordance with movement of said control element to and from its no-pressure supply position.

3. A drive control system including two couplings each independently operable by pressurized fluid to provide a driving connection between a load and a prime mover of torque capacity substantially proportional to the effective pressure of such fluid and operable upon release of such pressurized fluid to disconnect said load from said prime mover, a power control motor operable by pressurized fluid to adjust the speed of said prime mover in proportion to the pressure of such fluid, a control device operable to regulate fluid pressure for supply to said couplings and to said motor and including a control element movable between two maximum pressure supply positions through a no-pressure supply position, a first valve means including a valve member shiftable to selectively supply pressurized fluid from said control device to and to release pressurized fluid from either one of said couplings, a second valve means operable in response to a higher pressure of fluid in either one of said couplings to provide a connection between said power control motor and said one coupling whereby pressurized fluid as supplied to said coupling is supplied to operate said motor, and means associated with said control device for shifting said valve member to control the supply of fluid under pressure to and its release from each of said couplings in accordance with the movement of said control element to and from its no-pressure supply position, said last-mentioned means being operable upon operation of said control device element to or through its no-pressure supply position to shift said valve member to a position wherein said member is adapted to simultaneously release fluid under pressure from both of said couplings and to delay further movement of said valve member and thereby the supply of fluid under pressure to the other coupling to permit a reduction in the pressure of fluid in said one coupling below a chosen pressure.

4. A power plant drive control mechanism comprising, in combination, two friction couplings independently operable by fluid under pressure to provide alternative driving connections between a load and a prime mover of torque capacity substantially proportional to the pressure of such fluid and operable upon release of such fluid under pressure to disconnect said load from said prime mover, a power control motor operable by fluid above a predetermined pressure corresponding to that required to establish initial full engagement of such couplings to adjust the speed of said prime mover in proportion to the pressure of such fluid between minimum and maximum limits, a first valve means operable

to selectively supply and release fluid under pressure to and from said couplings, a second valve means operable in response to the supply of fluid under pressure to either one of said couplings to provide a connection between said one coupling and said motor to thereby supply such fluid under pressure to operate said motor, a control device operable to regulate the pressure of fluid supplied through said first and second valve means to said couplings and motor and including a control element movable between a no-pressure supply position and either of two full pressure supply positions, means for controlling operation of said first valve means to control the supply of fluid under pressure to and its release from each of said couplings and said motor in accordance with movement of said control element to and from its no-pressure supply position and operable upon movement of said control element to or through its no-pressure supply position to release fluid under pressure from either one of said couplings and said motor, and means associated with said last-mentioned means for delaying the supply of fluid under pressure to the other coupling until the pressure of fluid in said one coupling is reduced below a chosen pressure upon movement of said control element through its no-pressure supply position.

5. An apparatus for controlling two couplings independently operable by fluid under pressure to provide a driving connection between a load and a prime mover proportional to the pressure of such fluid and operable upon release of such fluid under pressure to disconnect said load from said prime mover and for also controlling a power control motor operable by fluid under pressure above a predetermined pressure to adjust the speed of said prime mover in proportion to the pressure of such fluid, comprising in combination with said couplings and motor, a first valve means operable to selectively supply fluid under pressure to and its release from said couplings, a second valve means operable in response to the supply of fluid under pressure to either one of said couplings to provide a connection between said one coupling and said motor to thereby supply such fluid under pressure to operate said motor, a control device operable to regulate the pressure of fluid supplied through said first and second valve means to said couplings and motor and including a control element movable from a no-pressure supply position to either of two full pressure supply positions, and means for controlling operation of said first valve means to control the supply of fluid under pressure to and its release from each of said couplings in accordance with movement of said control element to and from its no-pressure supply position, said last-mentioned means including means operable upon movement of said control element to or through its no-pressure supply position to permit relatively unrestricted actuation of said first valve means to release fluid under pressure from one of said couplings and to delay further actuation of said first valve means and thereby the supply of fluid under pressure to the other coupling to permit the pressure of fluid in said one coupling to be reduced below a chosen pressure.

6. An apparatus for controlling two couplings independently operable by fluid under pressure to provide alternative driving connections between a load and a prime mover of torque capacity substantially proportional to the pressure of such fluid and operable upon release of such fluid under pressure to disconnect said load from said prime mover and for also controlling a power control motor operable by fluid under pressure above a predetermined pressure to adjust the speed of said prime mover in proportion to the pressure of such fluid between minimum and maximum speed limits, comprising in combination with said couplings and motor, a first valve means operable to selectively supply fluid under pressure to either one of said couplings and at the same time release fluid under pressure from the

other coupling, a second valve means operable in response to the supply of fluid under pressure to either one of said couplings to provide a connection between said one coupling and said motor to thereby supply such fluid under pressure to operate said motor, a control device operable to regulate the pressure of fluid supplied through said first and second valve means to said couplings and motor and including a control element movable from a no-pressure supply position to either of two full pressure supply positions, means for controlling operation of said first valve means to control the supply of fluid under pressure to and its release from each of said couplings in accordance with movement of said control element to and from its no-pressure supply position and operable upon movement of said control element to or through its no-pressure supply position to cause said first valve means to release fluid under pressure from either one of said couplings, and interlock means operable in response to the pressure of fluid supplied to either one of said couplings to delay the supply of fluid under pressure to the other coupling upon movement of said control element through its no-pressure supply position until the pressure of fluid in said one coupling is reduced to below a predetermined pressure.

7. A drive control system including two couplings each independently operable by pressurized fluid to provide a frictional driving connection between a load and a prime mover proportional to the effective pressure of such fluid and operable upon release of such pressurized fluid to disconnect said load from said prime mover, a power control motor operable by pressurized fluid to adjust the speed of said prime mover in proportion to the pressure of such fluid, a control device operable to regulate fluid pressure for supply to said couplings and to said motor and including a control element movable between two maximum pressure supply positions through a no-pressure supply position, a first valve means including a valve member shiftable between first and second positions wherein said valve member is adapted to selectively supply pressurized fluid from said control device to either one of said couplings and at the same time to release pressurized fluid from the other coupling, said valve member having an intermediate position wherein it is adapted to simultaneously release pressurized fluid from both of said couplings, fluid pressure means associated with said control device for shifting said first valve member to its first and second positions to control the supply of fluid under pressure to and its release from each of said couplings in accordance with the movement of said control element to and from its no-pressure supply position, said last-mentioned means being operable upon operation of said control device element to or through its no-pressure supply position to shift said valve member to its intermediate position to insure release fluid under pressure from one of said couplings prior to the supply of fluid under pressure to the other coupling, and interlocking valve means operable to open said power control motor to said control device when said control device is supplying pressurized fluid to said first valve means in excess of a predetermined pressure.

8. A drive control mechanism comprising, in combination, two couplings independently operable by pressurized fluid to provide a frictional driving connection between a load and a prime mover of a torque capacity substantially proportional to the effective pressure of such fluid and operable upon release of such pressurized fluid to disconnect said load from said prime mover, a power control motor operable by pressurized fluid above a predetermined pressure to adjust the speed of said prime mover between minimum and maximum speed limits in proportion to the pressure of such fluid, a control device operable to regulate fluid pressure for supply to said couplings and to said motor and including a control element movable between two maximum pressure supply positions through a no-pressure supply position, said con-

trol device being adapted to supply pressurized fluid to one of said couplings sufficient to establish and maintain a substantially positive driving connection therethrough when said control device is supplying fluid pressure in excess of said predetermined pressure to said motor, a first valve means operable to selectively supply pressurized fluid from said control device to either one of said couplings and at the same time to release pressurized fluid from the other coupling, a second valve means operable to supply pressurized fluid from said control device to said motor, fluid pressure means associated with said control device and said first valve means for remotely controlling the operation of said first valve means to control the supply of fluid under pressure to and its release from each of said couplings in accordance with the movement of said control element to and from its no-pressure supply position, and a second fluid pressure means associated with said control device and said second valve means for remotely controlling the operation of said second valve means to control the supply of fluid under pressure to and its release from said motor in accordance with the movement of said control element to and from its no-pressure supply position.

9. A drive control system including two couplings individually operable by fluid under pressure to provide a controllable slip frictional driving connection between a load and a prime mover of a torque capacity substantially proportional to the effective pressure of such fluid below a predetermined pressure and to provide a substantially positive driving connection therebetween when the pressure of such fluid is above said predetermined pressure and operable upon release of such fluid under pressure to disconnect said load from said prime mover, a power control motor operable by fluid pressure above said predetermined pressure to adjust the speed of said prime mover in proportion to the pressure of such fluid, a coupling control pipe connected to each of said couplings, a speed control pipe connected to said power control motor, a first valve means intermediate said coupling control pipes and including a valve member shiftable in response to a differential in the fluid pressure in said coupling control pipes to interconnect the coupling pipe having the higher fluid pressure therein to said speed control pipe, a second valve means including a second valve member shiftable between two extreme positions for selectively supplying fluid under pressure to either one of said coupling control pipes while at the same time releasing fluid under pressure from the other coupling control pipe and having an intermediate position for simultaneously releasing fluid under pressure from both of said coupling control pipes, a double-acting motor means associated with said second valve means and operable by fluid pressure to selectively shift said second valve member toward either of its extreme positions, and means associated with said second valve means and operable upon release of fluid pressure from said double-acting motor means to shift said second valve member to its intermediate position, a control device operable to regulate fluid pressure for supply to said couplings and to said motor through said valve means and including a control element movable between two maximum pressure supply positions through a no-pressure supply position, and means associated with said control device and operable to selectively supply fluid pressure to said double-acting motor means to control the shifting of said second valve member to control the supply of fluid under pressure to and its release from each of said couplings and said power control motor in accordance with the movement of said control element to and from its no-pressure supply position, said last-mentioned means being operable upon operation of said control device element to or through its no-pressure supply position to release fluid pressure from said double-acting motor means to shift said second valve member to its intermediate position wherein it is adapted to simultaneously

release fluid under pressure from both of said couplings and to delay further movement of said valve member and thereby the supply of fluid under pressure to the other coupling to permit a reduction in the pressure of fluid in said one coupling below a chosen pressure.

10. A drive control system including two couplings individually operable by fluid under pressure to provide a controllable slip frictional driving connection between a load and a prime mover of a torque capacity substantially proportional to the effective pressure of such fluid below a predetermined pressure and to provide a substantially positive driving connection therebetween when the pressure of such fluid is above said predetermined pressure and operable upon release of such fluid under pressure to disconnect said load from said prime mover, a power control motor operable by fluid pressure above said predetermined pressure to adjust the speed of said prime mover in proportion to the pressure of such fluid, a coupling control pipe connected to each of said couplings, a speed control pipe connected to said power control motor, a valve having an inlet port connected to each of said coupling control pipes and an outlet port connected to said speed control pipe and including a valve member shiftable in response to a differential in the fluid pressure in said coupling control pipes to interconnect the coupling pipe having the higher fluid pressure therein to said speed control pipe, a four-way valve including a valve member shiftable between two extreme positions for selectively supplying fluid under pressure to either one of said coupling control pipes while at the same time releasing fluid under pressure from the other coupling control pipe and having an intermediate position for simultaneously releasing fluid under pressure from both of said coupling control pipes, a double-acting motor means associated with said four-way valve member and operable by fluid pressure to selectively shift said valve member toward either of its extreme positions, and means associated with said four-way valve member and operable upon release of fluid pressure from said double-acting motor means to shift said four-way valve member to its intermediate position, a control device operable to regulate fluid pressure for supply to said couplings and to said motor through said valves and including a control element movable between two maximum pressure supply positions through a no-pressure supply position, and means associated with said control device and operable to selectively supply fluid pressure to said double-acting motor means to control the shifting of said valve member to control the supply of fluid under pressure to and its release from each of said couplings and said power control motor in accordance with the movement of said control element to and from its no-pressure supply position, said last-mentioned means being operable upon operation of said control device element to or through its no-pressure supply position to release fluid pressure from said double-acting motor means to shift said four-way valve member to its intermediate position wherein it is adapted to simultaneously release fluid under pressure from both of said couplings and to delay further movement of said valve member and thereby the supply of fluid under pressure to the other coupling to permit a reduction in the pressure of fluid in said one coupling below a chosen pressure.

11. A drive control system comprising, in combination, two couplings individually operable by fluid under pressure to provide a controllable slip driving connection between a load and a prime mover of speed and torque capacity substantially proportional to the effective pressure of such fluid below a predetermined pressure and to provide a substantially positive driving connection therebetween when the pressure of such fluid is at or above said predetermined pressure and operable upon release of such fluid under pressure to disconnect said load from said prime mover, a power control motor operable by fluid pressure above a predetermined pressure to adjust the

speed of said prime mover in proportion to the pressure of such fluid, a speed control pipe connected to said power control motor, a first valve means operable to control the supply of pressure fluid to and from said speed control pipe, means associated with said first valve means and operable by fluid pressure to actuate said valve means to control the supply of pressure fluid to and from said speed control pipe, a coupling control pipe connected to each of said couplings, a second valve means operable between two extreme control conditions to selectively supply fluid under pressure to either one of said coupling control pipes while at the same time releasing fluid under pressure from the other coupling control pipe and an intermediate control condition for simultaneously releasing fluid under pressure from both of said coupling control pipes, motor means associated with said second valve means and operable by fluid pressure to selectively actuate second valve means to either of its extreme control conditions, and means associated with said second valve means and operable upon release of fluid pressure from said motor means to actuate said second valve means to its intermediate control condition, a control device operable to progressively regulate fluid pressure for supply to said couplings and to said motor through said valve means and including a control element movable between two maximum pressure supply positions through a no-pressure supply position, and means associated with said control device and operable to selectively supply fluid pressure to said valve means to control the actuation of said valve means to control the supply of fluid under pressure to and its release from each of said couplings and said power control motor in accordance with the movement of said control element to and from its no-pressure supply position.

12. An apparatus for controlling two individual couplings operable by fluid under pressure to provide a controllable slip driving connection between a load and a prime mover to a degree proportional to the pressure of such fluid below a predetermined pressure and to provide a substantially positive driving connection therebetween when the pressure of such fluid is above said predetermined pressure and operable upon release of such fluid under pressure to disconnect said load from said prime mover, and for also controlling a power control motor operable by fluid pressure to adjust the speed of said prime mover between minimum and maximum speed limits in proportion to the pressure of such fluid above said predetermined pressure, comprising in combination with said couplings and motor, a coupling control pipe connected to each of said couplings, a speed control pipe for said power control motor, a two-way check valve having an inlet port connected to each of said coupling control pipes and an outlet port connected to said speed control pipe and including a valve member shiftable in response to a fluid pressure differential in said coupling control pipes to interconnect the coupling pipe having the higher fluid pressure therein to said speed control pipe, a four-way valve means including a valve member shiftable between two extreme positions for selectively supplying fluid under pressure to either one of said coupling control pipes while at the same time releasing fluid under pressure from the other coupling control pipe and having an intermediate position for simultaneously releasing fluid under pressure from both of said coupling control pipes, a double-acting motor means associated with said four-way valve member and operable by fluid pressure to selectively shift said valve member toward its extreme positions, means associated with said four-way valve member and operable upon release fluid pressure from said motor means to shift said four-way valve member to its intermediate positions, and a control device including a control element movable from a no-pressure supply position to either of two full pressure supply positions to progressively regulate the pressure of fluid supplied through said four-way valve means to said couplings and motor, and shift valve means

operable in accordance with movement of said control element to and from its no-pressure supply position to selectively control the supply and release of fluid pressure to and from said double-acting motor means to thereby control the shifting of said four-way valve member to control the supply of fluid under pressure to and its release from each of said couplings and said motor.

13. A mechanism for controlling power transmission between a load and a prime mover comprising, in combination, a power control motor operable by fluid pressure above a predetermined pressure to adjust the speed of said prime mover in proportion to the pressure of such fluid, two couplings individually operable by fluid under pressure to provide a controllable slip driving connection between said load and said prime mover of a torque capacity substantially proportional to the effective pressure of such fluid below said predetermined pressure and to provide a substantially positive driving connection therebetween when the pressure of such fluid is above said predetermined pressure and operable upon release of such fluid under pressure to disconnect said load from said prime mover, a speed control pipe connected to said power control motor, a first flow control means associated with said speed control pipe and adapted to restrict the flow of fluid to said speed control motor and to permit the unrestricted venting of fluid from said motor, a coupling control pipe connected to each of said couplings, a first valve means intermediate said coupling control pipes and operable in response to a differential in the fluid pressure in said coupling control pipes to interconnect the coupling pipe having the higher fluid pressure therein to said speed control pipe, a second valve means operable between two extreme control conditions wherein fluid under pressure is selectively supplied to either one of said coupling control pipes while at the same time releasing fluid under pressure from the other coupling control pipe and an intermediate control condition wherein fluid under pressure is simultaneously released from both of said coupling control pipes, motor means associated with said second valve means and operable by fluid pressure to selectively actuate said second valve means toward either of its extreme control conditions and operable upon release of fluid pressure therefrom to shift said second valve means to its intermediate control condition, a control device operable to progressively regulate fluid pressure for supply to said couplings and to said motor through said valve means and including a control element movable between two maximum speed and load pressure supply positions through a neutral no-pressure supply position, a pressure supply pipe interconnecting said device and said second valve means, a second flow control means associated with said last-mentioned pipe and adapted to restrict the flow of fluid to said second valve means and to permit the relatively unrestricted venting of fluid from said second valve means, a third valve means associated with said control device and operable to selectively supply and release fluid pressure to and from said motor means to control the actuation of said second valve means in accordance with the movement of said control element to and from its no-pressure supply neutral position, and third flow control means intermediate said third valve means and said motor means and adapted to restrict the flow of fluid towards said motor means and to permit the relatively unrestricted venting thereof whereby operation of said control device element to or through its no-pressure supply position causes said third valve means to quickly vent fluid pressure from said motor means thereby causing said motor means to actuate said second valve means from one of its extreme control conditions to its intermediate control conditions wherein it is adapted to release fluid under pressure from the previously engaged one of said couplings and to delay actuation of said second valve means to its other extreme control condition and thereby the supply of fluid under pressure to the other coupling to permit a reduction in

the pressure of fluid in said one coupling below said predetermined pressure.

14. In a mechanism for controlling the transmission of power from a prime mover, the combination comprising a power control motor operable by fluid pressure above a predetermined pressure to adjust the speed of said prime mover in proportion to the pressure of such fluid, two couplings individually operable by fluid under pressure to provide a controllable slip frictional driving connection between a load and said prime mover of speed and torque capacity substantially proportional to the effective pressure of such fluid below said predetermined pressure and to provide a substantially positive driving connection therebetween when the pressure of such fluid is above said predetermined pressure and operable upon release of such fluid under pressure to disconnect said load from said prime mover, a speed control pipe connected to said power control motor, a first flow control means associated with said speed control pipe and adapted to restrict the flow of fluid to said speed control motor and to permit the unrestricted venting of fluid from said motor, a coupling control pipe connected to each of said couplings, a first valve means intermediate said coupling control pipes and operable in response to a differential in the fluid pressure in said coupling control pipes to interconnect the coupling pipe having the higher fluid pressure therein to said speed control pipe, a second valve means operable between two operating conditions wherein fluid under pressure is alternatively supplied to one of said coupling control pipes while at the same time releasing fluid under pressure from the other coupling control pipe and an intermediate operating condition wherein fluid under pressure is simultaneously released from both of said coupling control pipes, motor means associated with said second valve means and operable by fluid pressure to selectively actuate said second valve means toward either of its extreme operating conditions and operable upon release of fluid pressure therefrom to shift said second valve means to its intermediate operating condition, a control device operable to progressively regulate fluid pressure for supply to said couplings and to said motor through said valve means and including a control element movable between two maximum speed and load pressure supply positions through a neutral no-pressure supply position, a pressure supply pipe interconnecting said device and said second valve means, a second flow control means associated with said last-mentioned pipe and adapted to restrict the flow of fluid to said second valve means and to permit the relatively unrestricted venting of fluid from said second valve means, and a third valve means associated with said control device and operable to selectively supply and release fluid pressure to and from said motor means to control the actuation of said second valve means in accordance with the movement of said control element to and from its no-pressure supply neutral position.

15. In a mechanism for controlling power transmission between a load and a prime mover, the combination comprising a power control motor operable by fluid pressure above a predetermined pressure to adjust the speed of said prime mover in proportion to the pressure of such fluid, two couplings individually operable by fluid under pressure to provide a controllable slip driving connection between said load and prime mover of a speed and torque capacity substantially proportional to the effective pressure of such fluid below said predetermined pressure and to provide a substantially positive driving connection therebetween when the pressure of such fluid is above said predetermined pressure and operable upon release of such fluid under pressure to disconnect said load from said prime mover, a speed control pipe connected to said power control motor, a coupling control pipe connected to each of said couplings, a first valve means intermediate said coupling control pipes and operable in response to a differential in the fluid pressure in said coupling control pipes to intercon-

nect the coupling pipe having the higher fluid pressure therein to said speed control pipe, a second valve means operable between two extreme operational conditions wherein fluid under pressure is selectively supplied to either one of said coupling control pipes while at the same time releasing fluid under pressure from the other coupling control pipe and an intermediate operational condition wherein both of said coupling control pipes are simultaneously vented, motor means associated with said second valve means and operable by fluid pressure to selectively actuate said second valve means toward either of its extreme operational conditions and operable upon release of fluid pressure therefrom to shift said second valve means to its intermediate operational condition, a control device operable to progressively regulate fluid pressure for supply to said couplings and to said motor through said valve means and including a control element movable between two maximum speed and load pressure supply positions through a neutral no-pressure supply position, a pressure supply pipe interconnecting said device and said second valve means, and a third valve means associated with said control device and operable to selectively control the supply and release fluid pressure to and from said motor means to control the actuation of said second valve means in accordance with the movement of said control element to and from its no-pressure supply neutral position.

16. The combination set forth in claim 15 and including a flow control means intermediate said third valve means and said motor means and adapted to restrict the flow of fluid towards said motor means and to permit the relatively unrestricted venting thereof whereby operation of said control element to or through its no-pressure supply position causes said third valve means to quickly vent fluid pressure from said motor means thereby causing said motor means to actuate said second valve means to its intermediate operational condition wherein it is adapted to release fluid under pressure from one of said couplings, said flow control means delaying the supply of actuating pressure fluid to said motor means to effect further movement of said valve member towards its other extreme operational condition thereby delaying the supply of fluid under pressure to the other coupling to permit a reduction in the pressure of fluid in said one coupling below a chosen pressure.

17. The combination as set forth in claim 15 and including interlocking valve means intermediate said third valve means and said motor means and operable in response to the pressure of fluid supplied to either one of said couplings to permit relatively unrestricted venting of said motor means to return said second valve means to its intermediate operational condition from one of said extreme operational conditions upon actuation of said control element to or through its no-pressure supply position and to prevent the supply of fluid under pressure to said motor means to shift said second valve means towards the other of its extreme operational conditions and thereby the supply of pressure to the other of said couplings until the pressure of said one coupling is reduced to or below said predetermined pressure.

18. The combination set forth in claim 15 and including a flow control means intermediate said control device and said second valve means and adapted to restrict the flow of control device regulated pressure fluid towards said couplings and power control motor and to permit the relatively unrestricted venting of fluid therefrom, and relay valve means operable to bypass said flow control means in response to the supply of fluid above said predetermined pressure to said second valve means thereby permitting the relatively unrestricted supply of control device regulated pressure fluid through said second valve means to one of said couplings and said power control motor after a positive driving connection has been initially established through said one coupling.

19. In a mechanism for controlling transmission of power between a load and a prime mover, the combina-

tion comprising a prime mover control including a motor operable by fluid pressure to adjust the speed and torque capacity of said prime mover in proportion to the pressure of such fluid, a pipe connected to said motor, a first valve means associated with said pipe operable to control fluid flow therethrough, and means associated with said first valve means and operable by fluid pressure to actuate said valve means to control the supply of pressure fluid to and from said power control motor, two couplings individually operable by fluid under pressure to provide a controllable slip driving connection between said load and prime mover of a speed and torque capacity substantially proportional to the effective pressure of such fluid below a predetermined pressure and to provide a substantially positive driving connection therebetween when the pressure of such fluid is above said predetermined pressure and operable upon release of such fluid under pressure to disconnect said load from said prime mover, a pipe connected to each of said couplings, second valve means operable between two alternative operational conditions wherein fluid under pressure is selectively supplied to either one of said coupling connected pipes while at the same time releasing fluid under pressure from the other coupling connected pipe and an intermediate operational condition wherein both of said coupling connected pipes are simultaneously vented, double-acting motor means associated with said second valve means and operable by fluid pressure supplied to opposite ends thereof to selectively actuate said second valve means toward either of its alternative operational conditions and operable upon release of fluid pressure from both ends thereof to shift said second valve means to its intermediate operational condition, a control device operable to progressively regulate fluid pressure for supply to said couplings and to said motor through said first and second valve means and including a control element movable between two maximum speed and load pressure supply positions through a neutral no-pressure supply position, a pressure supply pipe interconnecting said device and said second valve means, a third valve means associated with said control device and operable to selectively control the supply and release fluid pressure to and from the opposite ends of said motor means to control the actuation of said second valve means in accordance with the movement of said control element to and from its no-pressure supply neutral position, and two pipes interconnecting said third valve means to opposite ends of said motor means.

20. In a mechanism for controlling transmission of power between a load and a prime mover, the combination comprising a power control motor operable by fluid pressure to adjust the speed and torque capacity of said prime mover in proportion to the pressure of such fluid, two couplings individually operable by fluid under pressure to provide a controllable slip driving connection between said load and prime mover of a speed and torque capacity substantially proportional to the effective pressure of such fluid below a predetermined pressure and to provide a substantially positive driving connection therebetween when the pressure of such fluid is above said predetermined pressure and operable upon release of such fluid under pressure to disconnect said load from said prime mover, a speed control pipe connected to said power control motor, a first valve means operable to control the supply of pressure fluid to and from said speed control pipe, means associated with said first valve means and operable by fluid pressure to actuate said valve means to control the supply of pressure fluid to and from said speed control pipe, a coupling control pipe connected to each of said couplings, second valve means operable between two extreme operational conditions wherein fluid under pressure is selectively supplied to either one of said coupling control pipes while at the same time releasing fluid under pressure from the other coupling control pipe and an intermediate operational condition

wherein both of said coupling control pipes are simultaneously vented, double-acting motor means associated with said second valve means and operable by fluid pressure supplied to opposite ends thereof to selectively actuate said second valve means toward either of its extreme operational conditions and operable upon release of fluid pressure from both ends thereof to shift said second valve means to its intermediate operational condition, and a control device operable to control the supply of fluid pressure to said couplings through said first valve means, said control device including a control element movable between two maximum speed and load positions through a neutral position, means for regulating fluid pressure for supply to said couplings and to said motor through said first and second valve means, said control device including a control element movable between two maximum speed and load positions through a neutral position, means for regulating fluid pressure for supply to said couplings and to said motor through said first and second valve means in accordance with movement of said control element from its neutral position towards either of its two maximum speed and load positions, a pressure supply pipe interconnecting said regulating means and said second valve means, a third valve means operable to selectively control the supply and release fluid pressure to and from the opposite ends of said motor means to control the actuation of said second valve means in accordance with the movement of said control element to and from its neutral position, and two shift control pipes interconnecting said third valve means to the opposite ends of said motor means.

21. In the combination as set forth in claim 20, said control device further including a means for reducing fluid pressure supplied thereto to a second predetermined pressure output, a fourth valve means operable by fluid pressure applied thereto above a third predetermined pressure to provide a first connection permitting fluid flow from said pressure regulating means through said pressure supply pipe to said second valve means and operable upon a release of fluid pressure therefrom to a pressure below said third predetermined pressure to provide a second connection permitting fluid flow from said pressure reducing means through said pressure supply pipe to said second valve means, a fifth valve means intermediate said two shift control pipes and operable in response to a differential in the fluid pressure in said two shift control pipes to connect the shift control pipe having the higher fluid pressure therein to said pressure reducing means, and a flow control means connecting said fourth valve means to the pressure supply connection intermediate said fifth valve and said pressure reducing means, said flow control means being adapted to restrict the application of actuating fluid pressure to said fourth valve means and to permit relatively unrestricted venting thereof thereby causing relatively rapid actuation of said fourth valve means to effect said second connection upon movement of said control element to or through its neutral position and to retard the actuation of said fourth valve means to effect said first connection upon movement of said control element from its neutral position.

22. In a mechanism for controlling transmission of power between a load and a prime mover, the combination comprising two couplings individually operable by fluid under pressure to provide a driving connection between said load and prime mover of torque capacity substantially proportional to the effective pressure of such fluid and operable upon release of such fluid under pressure to disconnect said load from said prime mover, a first valve means operable between two extreme operational conditions wherein fluid under pressure is selectively supplied to either one of said couplings while at the same time releasing fluid under pressure from the other coupling and an intermediate operational condition wherein both of said couplings are simultaneously vented, double-acting motor means associated with said first valve means and operable by fluid pressure supplied to opposite ends thereof to selectively actuate said first valve means toward either of its extreme operational conditions and operable upon release of fluid pressure from both ends thereof to shift said first valve means to its intermediate operational condition, a control device including a control element movable between two maximum speed and load positions through a neutral position, a second valve means operable to selectively control the supply and release fluid

tions and operable upon release of fluid pressure from both ends thereof to shift said first valve means to its intermediate operational condition, and a control device operable to control the supply of fluid pressure to said couplings through said first valve means, said control device including a control element movable between two maximum speed and load positions through a neutral position, means for regulating fluid pressure for supply to said couplings through said first valve means in accordance with movement of said control element from its neutral no-pressure supply position towards either of its two maximum speed and load pressure supply positions, a second valve means operable to selectively control the supply and release fluid pressure to and from the opposite ends of said motor means to control the actuation of said first valve means in accordance with the movement of said control element to and from its neutral position, two shift control pipes interconnecting said second valve means to the opposite ends of said motor means, a means for reducing fluid pressure supplied thereto to a predetermined constant pressure output, a third valve means operable by fluid pressure applied thereto above a second predetermined pressure to provide a first connection permitting fluid flow from said pressure regulating means through said pressure supply pipe to said first valve means and operable upon a release of fluid pressure therefrom to a pressure below said second predetermined pressure to provide a second connection permitting fluid flow from said pressure reducing means through said pressure supply pipe to said first valve means, a fourth valve means intermediate said two shift control pipes and operable in response to a differential in the fluid pressure in said two shift control pipes to connect the shift control pipe having the higher fluid pressure therein to said pressure reducing means, and a flow control means connecting said third valve means to the pressure supply connection intermediate said fourth valve and said pressure reducing means, said flow control means being adapted to restrict the application of fluid pressure to said third valve means and to permit relatively unrestricted venting thereof thereby causing relatively rapid actuation of said third valve means to effect said second connection upon movement of said control element to or through its neutral position and to retard the actuation of said third valve means to effect said first connection upon movement of said control element from its neutral position.

23. In a mechanism for controlling transmission of power between a load and a prime mover, the combination comprising two couplings individually operable by fluid under pressure to provide a controllable slip driving connection between said load and prime mover of a speed and torque capacity substantially proportional to the effective pressure of such fluid below a predetermined pressure and to provide a substantially positive driving connection therebetween when the pressure of such fluid is above said predetermined pressure and operable upon release of such fluid under pressure to disconnect said load from said prime mover, a first valve means operable between two extreme operational conditions wherein fluid under pressure is selectively supplied to either one of said couplings while at the same time releasing fluid under pressure from the other coupling and an intermediate operational condition wherein both of said couplings are simultaneously vented, double-acting motor means associated with said first valve means and operable by fluid pressure supplied to opposite ends thereof to selectively actuate said first valve means toward either of its extreme operational conditions and operable upon release of fluid pressure from both ends thereof to shift said first valve means to its intermediate operational condition, a control device including a control element movable between two maximum speed and load positions through a neutral position, a second valve means operable to selectively control the supply and release fluid

pressure to and from the opposite ends of said motor means to control the actuation of said first valve means in accordance with the movement of said control element to and from its no-pressure supply neutral position, means for regulating a first fluid pressure signal in accordance with movement of said control element from its neutral positions towards either of its two maximum speed and load positions, a means for generating a second fluid pressure signal proportional to the driven speed of said load, differential relay means operable in response to said first and second signals to regulate the supply of fluid pressure to said first valve means and thereby to either of said couplings, a second pressure regulating means associated with said differential relay means to limit the fluid pressure supplied to said first valve means to said predetermined pressure, said differential relay means being adapted to supply said predetermined pressure to said first valve means when said first signal pressure is in excess of said second signal pressure and to reduce the pressure of fluid supplied to said first valve

and said second signal approaches a pressure corresponding to that of said first signal pressure.

24. The combination as set forth in claim 23 and including a third valve means operable in accordance with the movement of said control element beyond a position wherein said first mentioned regulating means is conditioned to provide said first signal at said predetermined pressure to supply fluid to said first valve means in excess of said predetermined pressure bypassing said differential relay means to thereby insure against further slippage of either of said couplings.

CERTIFICATE OF CORRECTION

Patent No. 2,925,156

February 16, 1960

Arthur F. Grant et al.

It is hereby certified that error appears in the printed specification of the above numbered patent requiring correction and that the said Letters Patent should read as corrected below.

Column 3, line 67, after "speed" insert -- setting --; column 4, line 15, for "spede" read -- speed --; column 11, line 54, for "applied" read -- supplied --; column 15, line 28, for "104d" read -- 204d --; column 17, line 64, for "232"" read -- 232 --; column 22, line 12, for "sad" read -- said --; column 27, line 5, for "on" read -- one --; column 32, line 1, for "and" read -- as --.

Signed and sealed this 16th day of August 1960.
